UNITED STATES PATENT OFFICE.

FORREST H. JOHNSTON, OF TOLEDO, OHIO.

MUSIC-LEAF TURNER.

1,253,181.

Specification of Letters Patent.

Patented Jan. 8, 1918.

Application filed July 10, 1917. Serial No. 179,760.

To all whom it may concern:

Be it known that I, FORREST H. JOHNSTON, a citizen of the United States, residing at Toledo, in the county of Lucas and State 5 of Ohio, have invented new and useful Improvements in Music-Leaf Turners, of which the following is a specification.

This invention comprehends the provision of a music leaf turner, which can be conveniently operated by a slight touch of the 10 finger, when it is desired to turn a sheet of music, thus eliminating interruptions in the playing for this purpose, and allowing steady and proper time to be obtained.

15 The nature and advantages of the invention will be better understood when the following detail description is read in connection with the accompanying drawings, the invention residing in the construction, combination and arrangement of parts as claimed.

20 In the drawings forming part of this specification like numerals of reference indicate similar parts in the several views and 25 wherein:—

Figure 1 is a front elevation of a music leaf turner constructed in accordance with my invention.

Fig. 2 is a sectional view taken on line 30 2—2 of Fig. 1 looking from the top.

Fig. 3 is a sectional view taken on line 35 3—3 of Fig. 1 showing the manner in which the sheet carrying arms are held in normal position.

Fig. 4 is a similar view showing one of 40 the arms released.

Fig. 5 is a similar view showing the position of parts subsequent to the release of said section.

Fig. 6 is a perspective view of the sub-frame.

Fig. 7 is a sectional view taken on line 45 7—7 of Fig. 1.

The device forming the subject matter of my invention comprises an elongated base 10, from a point approximately central of which rises a post 11. Mounted upon the post 11 is a plurality of music sheet turning frames 12, two being shown in this particular instance, and each being of substantially U-shaped formation with their parallel limbs 13 disposed horizontally. Each frame 12 is provided with a hinge 14 adjacent the opposite extremities of the vertically disposed portion of the frame, while the hinges include a yoke 15 the terminals

of which are adapted to be received within holes or openings 16 in the post 11. In this manner the frames 12 are mounted for horizontal swinging movement, but it is to be observed that the yokes 15 are formed with collars 17 which serve to space the frames the requisite distance from the post 11 to permit of the proper swinging movement of the frame as will be readily understood. 60 Projecting from the base 10 are extensions 18 which are adapted to be arranged beneath the edge of the ordinary music rest of a piano or organ, it being understood that these rests are mounted for vertical swinging movement, and when the extensions 18 are placed beneath the rest the device will be properly supported upon the piano. 65

Mounted upon the base 10 and at the right side of the post 11 is a casing 19 in which is arranged the mechanism for holding the frames 12 normally at the right side of the post, and yet permit of the release of the frames singly, when it is desired to turn the sheet of music, at which time the particular frame released is swung to the left side of the post under the influence of one of the springs 20. The mechanism for this purpose preferably includes a horizontally disposed lever 21 which is pivoted at a point in its 75 length as at 22, the lever being provided with an inclined surface 23 and a shoulder 24. One end of the lever is secured to the adjacent extremity of a vertically disposed coil spring 25, the opposite extremity being secured to the bottom of the casing 19, the spring serving to normally maintain the lever 21 horizontally, and consequently operates to automatically return the lever to this position subsequent to any movement of the 80 lever. An arm 26 is vertically disposed within the casing and pivotally connected with the lever 21 as at 27, the arm projecting a slight distance above the lever 21 and the upper edge of the casing. A horizontally 85 disposed coil spring 28 has one end connected to the arm 26 adjacent its lower end, the opposite end of the spring being connected to the opposed wall of the casing, whereby the spring 28 serves to normally maintain 90 the arm 26 in right angular relation with respect to the lever 21. As shown in Fig. 3, the lower limbs 13 of the respective frames 12 are arranged behind the shoulder 24 of the lever 21 in the upper extremity of the 95 arm 26, and in this manner the frames are normally maintained at the right of the post.

100 105 110

When it is desired to turn the sheet of music supported by the frame arranged behind the shoulder 24, the lever 21 is moved upon its pivot to lower the shoulder 24 out of engagement with the said frame 12, thus releasing the latter and permitting the frame under the influence of one of the springs 20 to swing to the left hand side of the post. The lever 21 is actuated for this purpose by 10 depressing a finger actuating element 29 which is connected to the lever through the instrumentality of a trip rod 30. As shown in Fig. 4, when the lever 21 is actuated in the manner just described to effect a release of 15 one of the frames 12, the arm 26 assumes the position shown in Fig. 4, which holds the other frame against movement. When the lever 21 has been moved to its inactive position by depressing the element 29, the spring 20 20 is placed under tension, so that when pressure is removed from the element 29, the spring 25 functions to automatically return the lever to its normal position. However during the return movement of the lever 21 25 to its normal position, the arm 26 is moved to the position illustrated in Fig. 5, in which position it is out of the path of movement of the frame 12 with which it had been previously engaged. This frame under the influence of its associated spring 20, is moved 30 past the arm 26 into contact with the shoulder 24 of the lever. As the parts are brought to rest, the said section 12 is held at the right of the frame by reason of its engagement with the shoulder 24, until the element 29 is again depressed to actuate the lever 21 in the manner to effect a release of 35 said frame. In setting the device, the frames are merely swung to the right of the post 11, the inclined surface 23 of the lever preventing binding between the parts as the frames are swung into normal position, to engage behind the shoulder 24 of the lever and the upper extremity of the arm 26. Se- 40 cured to the uppermost limb 13 of each of the frames 12 is a flat spring 31 between which and the said limb the upper edge of the sheet of music is clamped. Projecting from the vertical portion 12 of each frame, 45 at a point approximately midway between the ends thereof is a wire rod 32 disposed in parallelism with the limbs 13, the rod 32 extending transversely of the sheet of music to facilitate the turning thereof as will be 50 readily understood.

In Fig. 6 I have shown a perspective view of what I term a sub-frame, this frame being disposed at the rear of the post 11, and which embodies a substantially L-shaped 55 base member 33 which extends transversely

of the post 11. Rising from the vertically disposed portion 34 of the frame is a pair of spaced wire elements 35 and 36 respectively of substantially inverted U-shaped formation, the elements 35 coöperating with the 60 horizontally disposed portion of the frame to support the front and back sheets of music, or what may be better termed the cover. The front and rear sheets of music rest against the wire elements 35 and 36 respectively, while the loose sheets are clamped upon the frames 12, and the latter subsequently positioned at the right of the post 11, and immovably held in this position by the mechanism hereinabove described. When it is desired to return the sheet of music next in order, the element 29 is depressed, thus releasing the frame supporting the particular sheet of music, in the manner hereinabove described, whereupon 70 the frame is swung to the left side of the post 11.

From the foregoing description it will be manifest that I have devised a means whereby a sheet of music can be quickly turned 75 when desired, without causing any interruptions in playing, and permitting the player to maintain steady and proper time. I desire to have it understood that what is herein shown and described constitutes the preferred embodiment of the invention to which I do not limit myself, and that such changes in the construction and arrangement of parts may be resorted to when desired as fall within the scope of what is claimed. 90

What is claimed is:—

A music leaf turner comprising a base, a post rising therefrom, a plurality of leaf supporting frames mounted upon the post for independent swinging movement, a 100 member on said base, a horizontally disposed lever pivoted in its length upon said member and formed to provide a shoulder along one edge to engage one of said frames, an arm pivoted to said lever with one extremity projected above said edge of the lever to engage the other of said frames, resilient means for normally holding the arm in right angular relation to said lever, means for rocking the lever to disengage 105 said shoulder from one of the frames, resilient means operating to automatically return the lever to horizontal position whereby said arm is disengaged from the other of said frames to permit the latter to engage the 110 shoulder when the lever assumes its normal position.

In testimony whereof I affix my signature.

FORREST H. JOHNSTON.
